TOWER CRANES

Pierre Durand, Lyons, France, assignor to Richier
(Societe Anonyme), Paris, France
Filed Oct. 24, 1965, Ser. No. 504,441
Claims priority, application France, June 14, 1965,
46,101, Patent 1,449,764
4 Claims. (Cl. 212—46)

The raising of a tower crane is generally performed through the incorporation in the tower of extensions constituted by independent sides or else by systems including several sides.

For the positioning of such extensions, the conventional method used for hoisting loads through the crane is resorted to, since it requires no auxiliary mechanism. Said conventional method cannot however be used under all circumstances, since, by reason of the location of the crane with reference to the surrounding obstructions, the jib cannot always operate on all the sides of the tower. It is true that arrangements have been proposed for erecting the crane while leaving the jib in a stationary position but such arrangements are intricate and often require a succession of intermediate steps and furthermore they are of interest only in the case of small and medium-sized cranes.

In the case of large cranes, the most advisable arrangement consists in resorting to a short auxiliary jib provided solely for such purposes and which is located generally at the upper end of the tower and is adapted to revolve around a vertical axis, so as to serve all the sides of the tower. Although such an arrangement is very convenient, yet it is expensive, since it requires the use of a second winch or at least of a second winch drum, said second winch or winch drum serving solely for the erection of the tower.

Now, my present invention allows eliminating this second winch or winch drum in cranes provided with a short jib to be used chiefly for adding extensions to the tower or removing such extensions for increasing or reducing correspondingly the height of the tower.

To this end, I engage the free end of the hoisting cable over the short jib which latter serves selectively for anchoring said free end during the conventional hoisting of loads and for guiding the cable during the hoisting of the extensions suspended to said cable at its free end.

In the first case corresponding to the conventional operation of the crane, the short jib forms the stationary point to which the free end of the cable is anchored. In the second case, corresponding to the hoisting of the extensions, the cable passes freely over the short jib and its free end may serve for engaging an extension or for engagement with the short jib after passing over a tackle carrying a hook by which an extension is suspended.

My invention will be readily understood from the reading of the following disclosure, reference being made to the accompanying diagrammatic drawings illustrating by way of example and in a non-limiting sense a preferred embodiment of my invention. In said drawings:

FIGS. 1 and 2 are side views of the upper part of a tower crane respectively during normal working periods and during the hoisting of an extension with a view to increasing the height of the tower.

In said figures, 2 designates the crane tower, 3 its conventional jib serving for the hoisting of loads, 4 the counterjib and 5 the short upper auxiliary jib serving for the raising of extensions such as 6 to be incorporated with the tower, so as to increase its heights. 7 designates the hoisting winch of which the cable 8 passes in succession over the pulleys 9, 10, 11 and over the pulleys and tackle secured to the carriage 12.

According to my invention, the cable passes in its section lying beyond the carriage 12 over three pulleys 13, 14a, 14b of which the two latter are carried by the

2

short jib provided with a terminal guide 15 engaged by the cable 8 the free end of which carries a hook 16.

When the crane is being used conventionally for hoisting loads, said hook 16 bears against the underside of the guide 15, that is against the end of the short jib. The rotation of the winch produces consequently, according to the direction of said rotation, a rising or a sinking of the hoisting hook 17; this corresponds therefore to the normal operative condition of the crane as illustrated in FIG. 1.

When it is desired to increase the height of the crane through incorporation of extensions 6, the same winch 7 is used, but the hoisting tackle has been operated so as to engage the underside of the carriage up to a locked position for which the hoisting hook 17 is secured to said carriage, so that it cannot sink again. A rotation of the winch in the opposite direction, that is in the downward direction results in a sinking of the hook 16 secured to the end of the cable 8. From said hook 16 may be suspended as illustrated in FIG. 2 an extension 6 the hoisting of which is effected by making the winch turn in the direction corresponding to upward movement.

The same winch 7 serves thus for hoisting selectively loads and extensions.

Obviously, my invention is not limited to the sole embodiment disclosed hereinabove by way of example and it covers in contradistinction all the modifications thereof falling within the scope of the accompanying claims. In particular, the free end of the cable may, beyond the pulley at the end of the short jib, pass over the pulley of a block carrying a hook from which an extension may be suspended, the cable passing beyond said pulley towards an anchoring point at the end of the short jib, so as to form thus a two-sided tackle.

What I claim is:

1. In combination with a crane tower adapted to incorporate extensions increasing its height, a main jib carried by the tower, a short jib carried by the tower, a carriage carried on the main jib for lengthwise movement along the main jib, a winch, a single cable controlled by said winch and trained about the carriage to form a depending load-hoisting loop beneath the carriage, said single cable extending over the outer end of said short jib, and hoisting means carried by that portion of the cable which extends over the outer end of the short jib, said hoisting means being movable vertically relative to the main jib so as to move tower extensions vertically relative to the main jib.

2. Apparatus as claimed in claim 1, said short jib being horizontally swingable relative to said main jib thereby to permit horizontal movement of said tower extensions relative to said main jib.

3. Apparatus as claimed in claim 2, and means for selectively individually fixing the vertical position of said hoisting means and said hoisting loop to allow operation of either independently of the other.

4. Apparatus as claimed in claim 1, and means for selectively individually fixing the vertical position of said hoisting means and said hoisting loop to allow operation of either independently of the other.
